UNITED STATES PATENT OFFICE.

BENJAMIN P. TERRELL, OF WARRENTON, NORTH CAROLINA.

FUSIBLE PLUG.

1,376,481.

Specification of Letters Patent.

Patented May 3, 1921.

Application filed October 28, 1919. Serial No. 333,999.

To all whom it may concern:

Be it known that I, BENJAMIN P. TERRELL, a citizen of the United States, residing at Warrenton, in the county of Warren and 5 State of North Carolina, have invented a new and useful Fusible Plug, of which the following is a specification.

This invention relates to new and useful improvements in steam boilers and more 10 particularly to low water alarms employed in connection therewith.

The primary object of the invention is to provide a device of this character which will permit the engine to proceed in the event 15 that the fusible plugs employed in connection with the boiler are caused to fuse, due to the collection of foreign matter thereon, which foreign matter often causes such fusing to take place, when the boiler has a sufficient quantity of water therein for the 20 efficient operation of the engine.

A further object of the invention is to provide means for directing the steam and water exhausting from the boiler when the 25 plugs are fused, to a point exteriorly of the fire box and in full view of the engineer, or at a point to eliminate all possibility of the operators of the engine being scalded or otherwise injured by the exhausting hot 30 water or steam.

A further object of the invention is to provide means disposed within a boiler for indicating before the water within the boiler has reached a dangerously low level, which 35 low level of water would impair the life of the crown sheet forming a part of the boiler.

A further object of the invention is to provide a device of this character including 40 a removable head supporting a plurality of fusible plugs the same being capable of application to a boiler from a point within the fire box of a locomotive thereby eliminating the necessity of entering the boiler for positioning the same.

45 A further object of the invention is to provide a head of this character which may be applied to the ordinary boiler construction now in use, without the necessity of changing or altering the construction 50 thereof.

With the foregoing and other objects in view which will appear as the description proceeds, the invention resides in the combination and arrangement of parts and in 55 the details of construction hereinafter described and claimed, it being understood

that changes in the precise embodiment of the invention herein disclosed, may be made within the scope of what is claimed, without departing from the spirit of the invention. 60

Referring to the drawing:

Figure 1 illustrates a diagrammatic view disclosing the application of the invention, to a boiler.

Fig. 2 illustrates a sectional view through 65 the device showing the interior construction thereof.

Referring to the drawing in detail, the device forming the subject matter of the present invention includes the head 5' which 70 is shown as applied to the crown sheet 6 of the usual boiler construction, the fire box 7 being shown as disposed directly under the crown sheet, in the usual manner.

The upper wall 8 of the boiler, is spaced 75 from the crown sheet 6, to contain water therebetween, which water is employed for generating the steam for running the locomotive engine. In the usual construction of boilers, the crown sheets are provided with 80 screw threaded openings, indicated at 9, which openings ordinarily accommodate a fusible plug, which, when the water within the boiler reaches a low level, melts, thus indicating that the water in the boiler is 85 dangerously low.

The invention includes a boiler having a crown sheet 6, and an upper wall 8, there being provided a suitable threaded opening in the crown sheet in which is positioned the 90 head 5', which is formed with a hollow portion 6', that is provided with a central partition 7', dividing the hollow portion 6' into adjacent compartments 8' and 9', the compartment 9' having communication with the 95 atmosphere through the pipe 10', extending through the upper wall of the boiler, one wall of the compartment 9' being provided with spaced openings 11' which accommodate the fusible plugs 12', and as shown, 100 these plugs are disposed in spaced relation with each other, so that the same will control different levels within the boiler.

The compartment 8' has communication with the atmosphere through the pipe 13', 105 which also extends through the boiler.

The hollow portion 6', is also provided with an opening 14', disposed adjacent the lower edge thereof, on a line with the upper surface of the crown sheet, in which the head 110 is positioned, so that the fusible plug 15', supported therein, will fuse, when the water

has reached the crown sheet, or when the water is exhausted from the boiler, thus permitting the steam to pass through the pipe 13', to the signal operated thereby.

5 In this construction, it is to be noted that when one signal has been sounded, indicating that the water in the boiler is reaching a low level, the valve member 16' is then operated to shut off communication between 10 the compartment 9' and atmosphere, thus permitting the engineer to replenish water and proceed to terminal, if however, the water reaches the danger point, or a point which would permit the crown sheet to be 15 burnt out, a signal is operated by the steam through pipe 13', as before described.

It might be further stated that the fusible plugs are often fused, due to the collection of foreign matter thereon, which foreign 20 matter covers one of the inner faces of the plugs, and prevents the same from contacting with the water within the boiler, which results in the plugs heating and fusing.

In the present invention, if the plugs fuse 25 when the boiler contains a quantity of water sufficient to allow the engine to operate, it is only necessary to close the valve 16', thus shutting off communication between the boiler and atmosphere, to the end that steam

may now be generated for the operation of 30 the engine.

It is believed that in view of the foregoing description a detail description of the operation of the device, step by step, is unnecessary for a clear understanding of the invention.

What is claimed is:—

In a boiler with a crown sheet having a threaded opening therein, a hollow plug positioned within the opening, a partition in 40 the plug and dividing the same into compartments, fusible plugs positioned in the walls of one compartment, and a fusible plug positioned in the wall of the opposed compartment, the fusible plug of the latter compartment being in closer relation with the crown sheet than the plugs of the opposite compartment, and means in communication with the respective compartments for providing communication between the compartments and the atmosphere. 45

In testimony that I claim the foregoing as my own, I have hereto affixed my signature in the presence of two witnesses.

BENJAMIN P. TERRELL.
